AMEBICIDAL COMPOSITIONS

Max C. McCowen, Indianapolis, Ind., assignor to Eli Lilly and Company, Indianapolis, Ind., a corporation of Indiana

No Drawing. Application November 18, 1954
Serial No. 469,863

5 Claims. (Cl. 167—65)

This invention relates to amebicidal compositions and more particularly to synergistic combinations of erythromycin and certain other amebicidal agents.

Erythromycin is an antibiotic substance which has been isolated from artificial nutrient culture media upon which the micro-organism *Streptomyces erythreus* has been grown. It is a useful and effective therapeutic agent for treatment of infections caused by Gram-positive organisms, and has also been found to be useful in the treatment of amebiasis.

When used therapeutically in the treatment of disease caused by amebic parasites, erythromycin must be employed in relatively large doses in order to secure effective results. Thus amounts of erythromycin ranging up to 400 mg. daily have been given for the treatment of amebiasis.

Certain other substances which have commonly been used for the treatment of amebiasis have likewise been required in relatively large dose amounts. For example, the arsenical drugs carbarsone and thiocarbarsone are generally administered therapeutically in doses ranging up to 500 mg. per day for a course of medication of ten days. Because these compounds are slowly excreted, rest periods are imperative to prevent cumulative toxic effects. Another effective amebicide is fumagillin, an antibiotic substance which is isolated from culture media upon which the micro-organism *Aspergillus fumigatus* has been grown. While fumagillin is a useful amebicide, having an effect on amebic parasites at relatively low dose levels, nevertheless, doses up to 200 mg. of fumagillin daily have heretofore been employed in an effort to bring about the cure of acute amebiasis. When such doses of this agent are given, untoward toxic symptoms may appear and generally require cessation of therapy.

It is an object of this invention to provide amebicidal compositions which are therapeutically effective in relatively low dosage. It is a further object of this invention to provide therapeutically useful amebicides which are substantially free from objectionable side effects. Other objects of the invention will be apparent from the disclosure made herein.

It has been found that by combining erythromycin with an amebicide of the group consisting of carbarsone, thiocarbarsone and fumagillin, highly effective compositions are obtained for use in the treatment of amebiasis. The agents, when combined, are synergistic: for example, the amount of erythromycin employed for therapeutic purposes in amebiasis can be reduced to one tenth or less of the amount of the usual therapeutic dose of erythromycin, while the other amebicides can be reduced in amount to one half or less of the normal therapeutic dose. The compositions are therefore therapeutically effective in dose amounts which are far less than would be expected to be required. Furthermore, because of the small quantity of each amebicidal agent which is present, the possibility of adverse side effects is substantially completely eliminated.

As an illustration of the synergistic amebicidal activity of the compositions of this invention, there is set forth in Table 1 hereinafter the result of experiments carried out in rats infected with *Endamoeba histolytica*. Young rats

5 were selected because the acute infection thus produced is more severe than in older rats, therefore providing more stringent experimental conditions. In the investigation, rats which were twenty-one days old and weighed from 30-35 g. were inoculated intracecally with cultures of 10 *Endamoeba histolytica* strain NIH 200. Eighteen hours later, they were treated orally with various amebicides and combinations of amebicides as noted hereinafter. From six to ten rats were treated on each dose level and four doses were given to each rat at regular intervals 15 over a period of two days. Forty-eight hours after the last dose had been given, the rats were sacrificed, the cecum of each rat was removed and the cecal contents were examined microscopically for the presence or absence of *E. histolytica* organisms. The microscopic observations were confirmed by subculture of the cecal contents in Shaffer-Frye medium incubated at 37° C. for forty-eight hours followed by repeated subculture in the same medium under the same conditions. A number 20 of inoculated, untreated rats were used as controls. The results observed were analysed statistically by the Chi-square method to determine the probability that the parasites were cleared from the animal. The results are set forth in the following table. The total dose of 25 each drug and combination of drugs given is set forth, together with the effect of the drug or combination expressed as cleared when the Chi-square probability values were 1 percent or less, or not cleared when those values were greater than 1 percent. In the case of lower dose levels of fumagillin, the results were such as to indicate 30 partial clearance, with Chi-square probability of 5 percent at the levels indicated, and this is recorded as such here, since fumagillin, as is known, has some effect upon *Endamoeba histolytica* at lower dose levels, without bringing about definite elimination of the organisms.

TABLE 1

	Drug	Total Oral Dose, mg./kg.	Result
45	Erythromycin	100 200 900 800	not cleared. Do. cleared. not cleared.
	Carbarsone	1,600	cleared.
50	Thiocarbarsone	100 365 700 3.3 5.6 10.0 45/225 45/450	not cleared. cleared. Do. partially cleared. Do. cleared. Do. Do.
	Fumagillin	45/225 100/100 20/400 45/225 45/110 100/50	Do. Do. Do. Do. Do.
55	Erythromycin/Carbarsone	100/1.6 100/3.0	Do. Do.
	Erythromycin/Thiocarbarsone	100/1.6 100/3.0	Do. Do.
	Erythromycin/Fumagillin	100/1.6 100/3.0	Do. Do.

60 While the relative amounts of each of the agents used in the new synergistic amebicidal compositions of the invention can be varied, and are reduced to quantities which are substantially less than those required for effective results in the case of each individual compound, it is preferred to use in the new compositions one portion comprising about 100 parts of erythromycin combined with a second portion of about 100 to 2000 parts of carbarsone, or about 50 to 500 parts of thiocarbarsone, or about 1 to 3 parts of fumagillin.

65 The compositions of the invention can be used therapeutically in various pharmaceutical forms. Thus, they

can be combined with suitable pharmaceutical extending media and excipients and compressed into tablets, or filled into gelatin capsules. Other pharmaceutical extending media can be employed with the compositions to produce suspensions, solutions, powders and the like.

The following examples illustrate the composition and use of the new amebicidal combinations of this invention.

Example 1.—Preparation of tablets containing erythromycin and carbarsone

The following ingredients are employed:		Grams
Erythromycin		1500
Carbarsone		1500
Starch		1750
Magnesium stearate		65

The erythromycin and carbarsone are thoroughly mixed with about 1450 g. of the starch. The mixture is granulated with a thin paste composed of about 175 g. of the starch with sufficient water. The granules thus produced are mixed with the remainder of the starch, and the magnesium stearate, and compressed into tablets having a total weight of about 475 mg. About ten thousand tablets, each containing 150 mg. of erythromycin and 150 mg. of carbarsone, are produced.

Alternatively, the tablets are prepared using part of the starch and the erythromycin to form compressed base tablets containing only the erythromycin. These tablets are placed in a coating pan and the carbarsone and the remainder of the starch are added thereto. With the pan rotating, aqueous gum acacia is added to cause the carbarsone and starch to adhere to the erythromycin tablets. In this way, a tablet is produced which contains as a core 150 mg. of erythromycin, and as an outer layer 150 mg. of carbarsone. An additional sugar coating may be applied in the usual way if desired, to provide protection and for pharmaceutical elegance.

For treating amebiasis, the tablets are administered orally in such amount and for such length of time as is necessary to clear the infection.

Example 2.—Preparation of a tablet containing erythromycin and thiocarbarsone

The following ingredients are employed:		Grams
Erythromycin		125
Thiocarbarsone		625
Starch		480
Magnesium stearate		20

The erythromycin and carbarsone are thoroughly mixed with about 330 g. of the starch. A thin paste is prepared by mixing about 100 g. of the starch with sufficient water, and the previously prepared mixture of erythromycin, thiocarbarsone and starch is granulated with the paste. The granules thus produced are mixed with the remainder of the starch and the magnesium stearate, and the whole is compressed into tablets having a total weight of about 500 mg., using a $\frac{1}{16}$ -inch die on the usual tableting machine. About 2500 tablets, each containing about 50 mg. of erythromycin and 250 mg. of thiocarbarsone, are produced.

Example 3.—Preparation of erythromycin-thiocarbarsone tablet

The following ingredients are employed:		G.
Erythromycin		100
Thiocarbarsone		50
Starch		112
Magnesium stearate		2

The erythromycin and thiocarbarsone are mixed with about 67 g. of starch, and the mixture is granulated with a thin paste containing 25 g. of starch. The granules are mixed with the remaining starch and the magnesium stearate and compressed on a tableting machine using $\frac{1}{32}$ -inch dies, to produce about one thousand tablets.

weighing about 264 mg. each, and containing about 100 mg. of erythromycin and 50 mg. of thiocarbarsone.

Example 4.—Preparation of tablets containing erythromycin and fumagillin

The following ingredients are employed.		G.
Erythromycin		300
Fumagillin		2.5
Lactose		120
Starch		222
Talc		10
Magnesium stearate		5

The erythromycin and fumagillin are thoroughly mixed with the lactose and about 120 g. of the starch. The mixture is granulated with a thin paste prepared from about 62.5 g. of starch with sufficient water, and the granules are mixed with the remainder of the starch, the talc and the magnesium stearate and compressed into tablets weighing about 265 mg. A $\frac{1}{32}$ -inch die set is employed for this purpose, using the usual tableting machine, and about 2500 tablets, each containing 120 mg. of erythromycin and 1 mg. of fumagillin, are obtained.

Example 5.—Preparation of tablets containing erythromycin and fumagillin

The following ingredients are employed.		G.
Erythromycin		365
Fumagillin		11.2
Lactose		100
Starch		166
Talc		5
Magnesium stearate		2

The erythromycin and fumagillin are mixed with the lactose and about 50 g. of the starch. The mixture is granulated with a paste prepared from 62.5 g. of the starch, and the granules are mixed with the remainder of the starch and the magnesium stearate. The mixture of all of the ingredients is then compressed into tablets having a total weight of about 264 mg. each, using a $\frac{1}{32}$ -inch die on the usual tableting machine. About 2500 tablets, each containing about 150 mg. of erythromycin and 4.5 mg. of fumagillin, are produced.

I claim:

1. A pharmaceutical composition comprising in combination, about 100 parts of erythromycin and a member selected from the group consisting of about 100 to 2000 parts of carbarsone, 50 to 500 parts of thiocarbarsone and 1 to 3 parts of fumagillin.
2. A pharmaceutical composition comprising one part of erythromycin and from about 1 to 20 parts of carbarsone.
3. A pharmaceutical composition comprising 100 parts of erythromycin and about 1 to 3 parts of fumagillin.
4. A pharmaceutical composition comprising 10 parts of erythromycin and 5 to 50 parts of thiocarbarsone.
5. A synergistic amebicidal therapeutic composition comprising in combination about 100 parts of erythromycin and a member selected from the group consisting of about 100 to 2000 parts of carbarsone, about 50 to 500 parts of thiocarbarsone, and about 1 to 3 parts of fumagillin, dispersed in a pharmaceutical extending medium.
